(57) **CLAIM**

The ornamental design for a basin, as shown and described.

DESCRIPTION

FIG. 1 is a top perspective view of a basin according to an embodiment of the claimed design;

FIG. 2 is a bottom perspective view of the embodiment of FIG. 1;

FIG. 3 is a front view of the embodiment of FIG. 1;

FIG. 4 is a rear view of the embodiment of FIG. 1;

FIG. 5 is a top view of the embodiment of FIG. 1; and, FIG. 6 is a bottom view of the embodiment of FIG. 1.

The broken lines in the drawings are for illustrative purposes only and form no part of the claimed design. Oblique shade lines show a translucent or transparent material.
